DESIGN FOR A COMBINED HOUSING AND BAG FOR A PORTABLE SURFACING TOOL

William E. Holt, Livingston, N. J.

Application April 4, 1939, Serial No. 84,030

Term of patent 7 years

To all whom it may concern:

Be it known that I, William E. Holt, a citizen of the United States, residing at Livingston, in the county of Essex and State of New Jersey, have invented a new, original, and ornamental Design for a Combined Housing and Bag for a Portable Surfacing Tool, of which the following is a specification, reference being had to the accompanying drawing, forming part thereof.

Fig. 1 is a perspective view of a combined hous-

ing and bag for a portable surfacing tool showing my new design; and

Fig. 2 is a perspective view looking at the opposite side of the tool.

I claim:

The ornamental design for a combined housing and bag for a portable surfacing tool, as shown.

WILLIAM E. HOLT.
